[57] CLAIM

The ornamental design for a combined warning light and siren housing for emergency vehicles, as shown and described.

DESCRIPTION

FIG. 1 is a front elevational view of the combined warning light and siren housing for emergency vehicles showing our new design, the rear elevational view being the mirror image of the front elevational view;

FIG. 2 is a top plan view thereof;

FIG. 3 is a bottom plan view thereof;

FIG. 4 is a left side elevational view thereof, the right side elevational view being the mirror image of the left side elevational view; and,

FIG. 5 is a perspective view taken from the front, left and top of the combined warning light and siren housing for emergency vehicles.
